UNITED STATES PATENT OFFICE.

SAMUEL GOLDEN, OF NEW YORK, N. Y., ASSIGNOR TO HULLFIN BOAT COMPANY, INC.,
OF NEW YORK, N. Y., A CORPORATION OF NEW YORK.

HULL FOR VESSELS.

1,294,082.

Specification of Letters Patent. Patented Feb. 11, 1919.

Application filed October 19, 1917. Serial No. 197,460.

To all whom it may concern:

Be it known that I, SAMUEL GOLDEN, a citizen of the United States, and resident of the borough of Manhattan, in the city and State of New York, have invented a new and useful Improvement in Hulls of Vessels, of which the following is a specification.

This invention relates to improvements in hulls of vessels, and particularly to those which are designed to be propelled by screw propellers and which are of the type shown and described in my Patent No. 867,654, dated October 8, 1907, upon which structure this invention is an improvement.

One object of my invention is to provide such a structure in which increased speed may be obtained as a result of the design of the hull and the location and arrangement of the propelling mechanism.

Another object is to provide such a structure in which the qualities of sea-worthiness, easy handling and maneuvering, as well as stability, are greatly increased.

A still further object consists in providing certain improvements in the construction, form and arrangement of the several parts whereby the above named and other advantages may be effectively attained.

A practical embodiment of my invention is represented in the accompanying drawings, in which,

Figure 1 represents a side elevation of a vessel embodying my invention.

Fig. 2 represents a bottom plan view of the same.

Fig. 3 represents a stern elevation of the same, minus the superstructure.

Fig. 4 represents a bow elevation of the parts shown in Fig. 3.

Fig. 5 represents an enlarged interior elevation of one of the auxiliary fins, partly in section.

Fig. 6 represents a top plan view of the parts shown in Fig. 1, together with a section of the wall of the main fin to which the auxiliary fin is attached.

Fig. 7 represents a transverse section on the scale of Figs. 5 and 6, through the auxiliary fin and the main fin to which it is attached.

Fig. 8 represents a detail plan view, partly in section, showing a modified form of drive

from the motor in the main fin to the shaft in one of the auxiliary fins.

Fig. 9 represents an enlarged detail side elevation, partly in section, on a scale intermediate that of Figs. 1 to 4 inclusive and that of Figs. 5 to 8 inclusive, of a modified form of fin arrangement; and

Fig. 10 is a detail inverted plan view of the parts shown in Fig. 9.

Referring to the preferred form shown in Figs. 1 to 7 inclusive, the hull of the vessel is denoted by 1, and it is provided on its bottom with a hollow compartment or fin 2 which is built into the vessel so as to be in communication with the hull thereof.

This main fin 2 is both shorter and narrower than the bottom of the hull 1, and is preferably disposed about centrally thereof; that is, the main fin is arranged so that its front part is about the same distance from the stem of the hull as its rear part is from the stern, and each of its sides is substantially the same distance from the adjacent sides of the hull.

I prefer to have the main fin 2 with its greatest width forward of its center, and tapered both forwardly, rearwardly and downwardly so as to have somewhat the shape of a fish or torpedo, in order that it may cut through the water with a minimum of resistance.

Within the main fin 2, I provide a suitable motor 3, from which a propeller shaft 4 extends through the rear end of the main fin and is fitted with a screw propeller 5. Of course, suitable bearings and stuffing-boxes will be arranged in connection with the shaft 4, in a well understood manner.

A bracket or guide 6 projects rearwardly from the main fin 2, and is intended to act as the lower pivot point for a rudder 7, as well as to protect the screw propeller 5 of the said rudder.

Upon each side of the main fin 2, I locate auxiliary fins 8, 9. These auxiliary fins are preferably of substantially the same shape as the main fin 2, for the purpose already named, and they may appropriately be composed of two sections constructed of wood or other suitable material fastened together and riveted or otherwise secured to the main fin 2. The combined construction is such that

communication is open between the main and auxiliary fins.

I preferably divide each of the auxiliary fins into three separate compartments, as shown in Figs. 5 and 6, by means of transverse partitions 10, 11, and it is the central compartment which is required to be in communication with the interior of the main fin 2.

10 A tubular propeller shaft housing 12 is threaded into a mounting 13 fixed to the partition 11 in each of the auxiliary fins, and extends rearwardly to the tail of each fin in which it is suitably secured. The rear end 15 of the said housing may have appropriate propeller shaft bearings located therein, as indicated at 14, for the journaling of the auxiliary propeller shafts 15, while the mounting 13 is equipped with the customary 20 stuffing-box 16 for preventing the ingress of water.

The auxiliary propeller shafts 15 are directly connected to suitable motors 17 and have their rear ends equipped with screw 25 propellers 18.

I prefer to mount the main propeller 4 and the auxiliary propellers 15 horizontally, and parallel with each other, which arrangement I am enabled to obtain as the 30 result of the peculiar construction herein described, since the motors, instead of being up in the hull of the vessel, are down on a line with the propellers.

From the foregoing description it will be 35 seen that I have devised an arrangement in which the weight of the source of motive power is held low, and in which the propellers have a straight-line drive, and are maintained in solid water irrespective of 40 the rolling or tossing of the vessel. Furthermore, the under-water structure, while serving all the purposes of main and bilge 45 keels, is also adapted to accommodate the machinery and thus leave the hull of the vessel free for cargo or passenger space.

By reason of the fact that the fins are narrow and fish shaped, they will offer very little resistance to the progress of the vessel and, since they are materially shorter 50 than the hull, the maneuvering of the vessel is greatly facilitated. The auxiliary propellers may be utilized for steering the vessel, in case the gear designed for that purpose is out of order, or they may be used as 55 the sole means for propelling the vessel in case the main motor or associated parts are incapacitated.

It will be noted further that all the propellers are somewhat above the extreme bottom of the vessel so that they will not be damaged in case the vessel grounds moderately.

Referring to the modified form shown in Fig. 8, the parts are the same as those embodied in the preferred form, except that the auxiliary shafts, instead of being con-

nected with independent motors, are merely provided with sprockets 19 which are connected by chains 20 with sprockets 21 on the main shaft 4.

Referring to the modified form shown in 70 Figs. 9 and 10, it is the same in all respects as the preferred form except that two auxiliary fins are located upon each side of the main fin.

I desire to emphasize the fact that the 75 construction described results in an increased efficiency in the propulsion of the vessel; that is, in an increased speed for a given motive power, over that of previous structures within my knowledge, as well as 80 greater stability and ease in handling or maneuvering of the vessel. The former advantages obtain mainly because a straight-line drive is provided and because the propellers are maintained in solid water where- 85 in their full effect may be exerted. The latter advantages result chiefly from the general construction and arrangement of the main and auxiliary fins and their location upon the hull of the vessel.

It will be understood that various changes 90 may be resorted to in the form, construction and arrangement of the several parts without departing from the spirit and scope of my invention, and hence I do not intend to 95 be limited to the specific details herein described except as they may be included in the claims.

What I claim is:

1. A structure of the character described 100 comprising, a hull, a main hollow fin of less width and length than the hull formed on the bottom thereof, an auxiliary hollow fin formed on the main fin, a propeller shaft mounted in the auxiliary fin and projecting 105 through one end thereof, the outer surface of the main fin adjacent the projecting end of the shaft being substantially free of obstructions whereby a propeller carried by the said end of the shaft may operate in 110 solid water, and means carried by the said fins for actuating the propeller shaft.

2. A structure of the character described comprising a hull, a main hollow fin of less width and length than the hull formed on 115 the bottom thereof, a plurality of auxiliary hollow fins formed on the main fin, propeller shafts mounted in the auxiliary fins and projecting through an end thereof, the outer surface of the main fin adjacent the 120 projecting ends of the shafts being substantially free of obstructions whereby propellers carried by the said ends of the shafts may operate in solid water, and means carried by the said fins for actuating the pro- 125 peller shafts.

3. A structure of the character described comprising a hull, a main hollow fin of less width and length than the hull formed on the bottom thereof, a plurality of auxiliary 130

hollow fins formed on each side of the main fin, propeller shafts mounted in the auxiliary fins and projecting through an end thereof, the outer surface of the main fin adjacent the projecting ends of the shafts being substantially free of obstructions whereby propellers carried by the said ends

of the shafts may operate in solid water, and means carried by the said fins for actuating the propeller shafts.

In testimony, that I claim the foregoing as my invention, I have signed my name this 16th day of October, 1917.

SAMUEL GOLDEN.
